H. A. Druckman
ATTORNEY.

UNITED STATES PATENT OFFICE

EUGENE W. DODGE, OF LONG BEACH, CALIFORNIA

OIL PUMP

Application filed November 25, 1929. Serial No. 409,457.

This invention relates to a pump, particularly applicable to the pumping of oil wells and the like.

An object of my invention is to provide a novel means whereby sand or sediment is kept agitated and prevented from packing tightly in the lower part of the barrel or if any substance becomes tightly packed or solidified, such substance will be broken up during the 10 operation of the pump.

Another object is to provide a novel means whereby the standing valve is raised to drain the pump and tubing.

A further object is to provide a novel packing means for the inner plunger whereby a more effective seal is provided for said plunger.

Other objects, advantages and features of the invention may appear from the accompanying drawing, the subjoined detailed description and the appended claims.

In the drawing:

Figure 1 is a fragmentary, longitudinal sectional view of my pump.

Figure 2 is a fragmentary side elevation of the pump.

Referring more particularly to the drawing, the numeral 1 indicates a bushing, which bushing is provided with threads at the upper end thereof to receive a cage or the like (not shown), said cage being usual and well-known in this type of pump. A tube 2 screws on to the lower end of the bushing 1 and depends therefrom.

A standing valve shoe 3 of any usual and well-known construction is provided at the lower end of the pump, and this shoe fits into a member at the bottom of the tubing, all of which will be readily understood by those skilled in the art. A barrel 4 is secured to the upper end of the shoe 3 and rises a considerable distance above the shoe. The barrel 4 is substantially the same length as the tube 2. This last named tube fits over the barrel 4 and reciprocates thereon as will be further described.

A pipe 5 screws into the bushing 1 and extends downwardly from the bushing into the barrel 4. An upper plunger head 6 is secured to the lower end of the pipe 5, prefer-

ably by being screwed thereon. A ball housing 7 forms the lower member of the plunger, and this housing and the head 6 are connected together by a perforated tubing 8 which screws into both the head and the housing. A plurality of perforations 9 are provided in the tubing 8 and the purpose of these perforations will be further described.

A fibrous or expandable metal packing 10 fits around the perforated tubing 8 and between the head 6 and the housing 7. The packing fits closely against the inside of the barrel 4, thereby a tight seal for the plunger. The weight of the liquid above the pump will be exerted through the perforations 9 and will expand the packing 10 outwardly against the wall of the barrel. As the packing wears, it will expand more and more outwardly until it has been practically worn through. It will be seen that with this arrangement the usual wear in the pump will be compensated for, and there will be little need for replacement of the plunger except at very infrequent intervals.

A ball seat 11 is provided in the housing 7 and a ball check 12 rests on the seat. The purpose of this ball is to prevent the fluid from flowing downwardly upon the standing valve and also to enable the pump to lift on its up stroke. A cage 13 screws on the lower end of the housing 7 and a chain 14 is secured to the lower end of this last named cage. A seat 15 is provided in the shoe 3 and a ball 16 rests on this last named seat. This ball and seat form the standing valve.

A wash-out cage 17 fits in the shoe 3 and is provided with a plurality of inwardly extending fingers 18 which are adapted to engage the ball 16 when the cage is raised as will be further described. The chain 14 is secured to the upper end of the cage 17 and when the bushing 1 is pulled upwardly so as to make the chain 14 taut through the medium of the plunger, the cage 17 will be raised, thus removing the ball 16 from its seat and the sand or other sediment will be allowed to drain downwardly through the seat 15.

A coil spring 19 bears against the top of the cage 17 and against a shoulder 20 in the shoe 3, and the purpose of this spring is to

normally hold the cage 17 downwardly so that the action of the ball 16 will not be interfered with. In order that the tubing may be drained when the ball 16 is lifted, I

5 provide slots 21 in the tube 2 which register with ports 22 in the barrel when the tube is in the elevated position which causes the chain 14 to tighten and raise the ball 16 off of its seat. The fluid will then drain into the

10 pump below the cage 13, and will flow past the standing valve back into the casing. This action will also flush all of the sand or sediment from around the cage 17, and will thoroughly cleanse the pump.

15 It will be evident from the foregoing description that my pump can be removed in its entirety from the well by reason of the chain 14. When the pump is removed, the chain acts as a garbot rod. If desired, the

20 chain 14 may be any type of flexible metallic member, such as metal hose which telescopes, or the like. If the sucker rods should part, and if a fishing tool must be screwed on to the parted rods, I provide a means of lock-

25 ing the shoe 3 and the tube 2, which means consists of upstanding lugs 23 on the upper end of the shoe which fit into rests 24 in the bottom of the tube 2.

The chain 14, during the normal operation

30 of the pump hangs loosely in the barrel with several links coiling above the cage 17. The reciprocation of the plunger will move the chain constantly, thus breaking up or loosening any sand or sediment which might tend

35 to settle and pack in the lower part of the pump. It will also be evident from the foregoing description that my pump can be cleaned out by raising the standing valve ball from the inside and without requiring any

40 additional tools to be run into the hole.

Having described my invention, I claim:

1. In a pump including a standing valve shoe, a barrel rising from the shoe, a plunger in the barrel, a ball check in said shoe, a

45 washout cage in the shoe, engaging said ball, and a coiled spring bearing against the top of said washout cage whereby the cage is urged downwardly, and a chain secured to said cage, and to the barrel, said washout

50 cage being adapted to be lifted, against the tension of the spring, and simultaneously lift the ball check from its seat.

2. In a pump including a standing valve shoe, a seat positioned in the shoe, a ball

55 resting on said seat, a washout cage above the seat, said cage engaging the ball, a shoulder in the shoe, a coil spring bearing against the shoulder and against the top of the washout cage, a barrel rising from the shoe, a plunger

60 in the barrel, and a chain secured to the lower end of said plunger and to the washout cage whereby said cage may be lifted to unseat said ball.

In testimony whereof, I affix my signature.
EUGENE W. DODGE.
